(No Model.)

H. KENNEDY.
GAS BURNER.

No. 469,824.

Patented Mar. 1, 1892.

UNITED STATES PATENT OFFICE.

HUGH KENNEDY, OF SHARPSBURG, PENNSYLVANIA.

GAS-BURNER.

SPECIFICATION forming part of Letters Patent No. 469,824, dated March 1, 1892.

Application filed January 19, 1891. Serial No. 378,185. (No model.)

To all whom it may concern:

Be it known that I, HUGH KENNEDY, of Sharpsburg, in the county of Allegheny and State of Pennsylvania, have invented a new and useful Improvement in Gas-Burners, of which the following is a full, clear, and exact description, reference being had to the accompanying drawings, forming part of this specification, in which—

10 Figure 1 shows my improved burner in side elevation, partly in vertical section, on the line II of Fig. 2. Fig. 2 is a front view thereof; and Fig. 3 is a side elevation on a smaller scale, showing a modified construction of the mechanism for moving the burner-valve.

15 My improved burner has been devised especially for burning blast-furnace gases in the furnaces of steam-boilers, &c. Such gases are difficult to burn with economy and good 20 results; but by means of my improvement I am enabled to utilize their heating qualities to the best advantage.

25 My invention also affords means by which the burner may be used as an efficient device for regulating the supply of gas, or, if need be, cutting it off altogether.

In the drawings, 2 represents the combustion-chamber of a boiler-furnace. The gas for the furnace is derived from a pipe or conduit 3, the mouth of which is faced by a plate 4, having a port or opening registering with the conduit. The burner consists of a goose-neck pipe 5, whose delivery end is elongated in width horizontally and is relatively narrow in vertical dimension. This pipe when in operation enters partially a hole 6, formed in the wall of the combustion-chamber, and the hole is larger in dimensions than the end of the pipe, so that a considerable vacant 35 space is left around the latter, through which the entering gas, expanding in the opening, induces a supply of air into the furnace. The pipe 5 is carried by a valve-plate 7, which is set on the plate 4 and is movable thereon by 40 means of a lever 8 or other appliance. This lever 8 is connected with the pipe 5 by a link 9, and is provided at the bottom with a cross-bar 10, adapted to engage notches in fixed side bars 11. By pulling on the lever and, 45 when necessary, shifting the cross-bar 10 from one set of opposite notches to the next, the

burner-pipe and its supporting-plate may be moved as desired.

In the modification shown in Fig. 3 the lever is pivoted to a stationary pivot 12, and the link 9 is notched, and its notches are adapted to engage and to be shifted on a pin 13 on the lever to afford it a greater range of action, as in Fig. 1. By operating this lever as above described the plate 7 may be moved, 55 so that the end of the pipe shall register with the conduit 3 and shall be adapted to receive gas therefrom, or it may be moved back, so as to disconnect the pipe from the conduit and to close the conduit by covering it with the 60 plate 7 and to cut off the supply of gas to the burner.

When the parts are in the position shown in Fig. 1, the gas passes through the burner-pipe and through the opening 6 into the combustion-chamber 2, and being delivered from a small hole in the pipe it expands in the opening 6, and thereby induces with strong suction a supply of air, as indicated by the arrows b. The size of the opening 6 is so proportioned to the size of the delivery-opening of the burner that a proper amount of air 70 shall be induced to mingle with the gas to cause the best results in combustion. The proportional size illustrated in the drawings 75 is proper to cause the entrance of sufficient volume of air to burn the gas without any other air-inlet. This is desirable because it causes the combustion to begin at the very front of the combustion-chamber, and thus 80 supplies greater and more rapidly-acting heat to the boiler. The gas enters in a wide thin sheet, so that it mingles at once with the air and produces the most effective combustion, and when ignited the wide flame passes 85 under the boiler and affords thereto a maximum of heat. By moving the plate 7 back on its seat, as above indicated, the gas-opening may be partially or entirely cut off and the size of the flame thus regulated, as may 90 be desired.

Divers modifications in the form and relative arrangement of the parts of the mechanism may be made by the skilled mechanic without varying from the invention as stated in the 100 following claims, each of which states an item of invention unqualified by peculiar limita-

tions expressed in the other. Thus it will be understood that I intend to claim, broadly, the burner having a discharge end of the shape indicated, whether it be set on a movable 5 valve-plate or not.

By the words "gas-blast-producing apparatus" in the claims I intend to cover any apparatus whereby a pressure is produced upon the gas, so that it may draw in the air as it 10 issues from the burner-tube.

I claim—

1. In combination, a gas-blast-producing apparatus, a delivery-pipe leading therefrom of substantially as large area as the burner 15 to which it leads, flattened at its delivery end to form an open-mouthed burner wide in one dimension and relatively thin transversely, a furnace into which said burner leads, and an

air-inlet space around the burner, substantially as and for the purposes described. 20

2. The combination, with a gas-burner and valve-plate attached thereto, of a projecting piece rigidly attached to the burner, a link pivotally connected to the projecting piece, a lever engaging said link, said lever having 25 a pivotal bolt passing therethrough, a separate pin projecting from its side, and a slotted bearing for the pin, substantially as and for the purposes described.

In testimony whereof I have hereunto set 30 my hand this 10th day of January, A. D. 1891.

HUGH KENNEDY.
